ATTORNEY

UNITED STATES PATENT OFFICE.

EDWARD L. KNOWLES, OF ALLIANCE, OHIO.

HOLDER.

1,370,122.

Specification of Letters Patent.

Patented Mar. 1, 1921.

Application filed May 17, 1920. Serial No. 382,092.

To all whom it may concern:

Be it known that I, EDWARD L. KNOWLES, a citizen of the United States, residing at Alliance, in the county of Stark and State 5 of Ohio, have invented new and useful Improvements in Holders, of which the following is a specification.

The present invention has reference to a vase holder for cemetery use.

10 The object is to produce a simple, cheap and effective device of this character whereby a vase may be securely gripped and supported, and readily removed when occasion requires.

15 A further object is to construct from strands of wire a central post or standard that is designed to be forced into the earth that has at its outer end oppositely disposed spring jaws designed to clamp therebetween 20 a vase.

The foregoing objects, and others which will appear as the nature of the invention is better understood, may be accomplished by a simple construction, combination and arrangement of parts, such as is disclosed by 25 the drawing.

The drawing illustrates a perspective view of the improvement.

In carrying out my invention, I employ 30 two strands of spring wire. These strands are rounded outwardly, at the center thereof to provide lips 1. From the lips the parallel strands 2 provide arms 3. These arms, at approximately the center thereof are ex- 35 tended outwardly in the same plane as indicated by the numeral 3', and are from thence extended inwardly as at 4. The elements above described comprise the jaw portions of the device, and by reference to the 40 drawing it will be seen that the jaws are

reversely arranged. It will also be noted that the elements 4 of the jaw member are directed toward each other, and the strands constituting the same are then extended angularly in contacting relation to provide the 45 upper spaced portions 5 of the stem 6. The strands constituting the spaced members 5 are extended at an inclination toward each other, as at 7, and each of the double strands is brought into contacting engagement and 50 further extended to provide the stem 6. The stem 6 is forced into the ground. The device, being constructed of spring wire, allows the jaws to be readily spread away from each other so as to receive a vase there- 55 between. The portions 4 are extended from the portion 3 at an inward angle, so that these portions provide a rest for the bottom of the vase. However, when a conical vase is employed the pointed end thereof may be 60 received between the portions 5 of the de- 65 vice, and it is thought that the foregoing de- 70 scription, when taken in connection with the drawing will fully set forth the simplicity and advantages of the device to those skilled 75 in the art to which such inventions relate.

Having thus described the invention, what I claim, is:-

A vase holder comprising opposed spring jaws, each having its outer end formed with 70 a rounded lip from which extend parallel side arms that are bent angularly in an out- 75 ward direction and from thence extended in- wardly and at their points of contacts are extended in parallelism with each other and bent upon themselves to provide a straight stem.

In testimony whereof I affix my signature.

EDWARD L. KNOWLES.
